UNITED STATES PATENT OFFICE.

AUGUST D. COOK, OF LAWRENCEBURG, INDIANA.

DESIGN FOR A WELL-STRAINER.

SPECIFICATION forming part of Design No. 26,775, dated March 16, 1897.

Application filed January 7, 1897. Serial No. 618,419. Term of patent 14 years.

To all whom it may concern:

Be it known that I, AUGUST D. COOK, a citizen of the United States, residing at Lawrenceburg, in the county of Dearborn, State of Indiana, have invented and produced a new and original Design for Well-Strainers, of which the following is a specification, reference being had to the accompanying drawings, showing a part thereof.

10 Figure 1 is a perspective view of a well-strainer embodying my design. Fig. 2 is a vertical sectional view of the same shown exaggerated. Fig. 3 is a transverse sectional view of the strainer through the slits or openings. These views are deemed necessary to illustrate my design.

The leading feature of my design consists in a series of vertical rows of transversely-disposed elongated slits or openings formed 20 in the wall of the strainer, such strainer, as is well known, being of a general tubular shape. The slits or openings are formed at regular intervals and at a right angle to the external surface of the strainer. The outer portions of these slits or openings, say for about a 25 quarter of their length or depth, have their upper and lower surfaces parallel, but beyond said point the surfaces are concaved in a gradual manner.

A represents the wall of the strainer; B, the 30 outer portions of the slits or openings; C C, the parallel surfaces of the slits or openings, and D D the flared concaved surfaces of the same.

What I claim is—

The design for well-strainers herein shown and described.

In testimony whereof I affix my signature in presence of two witnesses.

AUGUST D. COOK.
